Primary Examiner — T. Chase Nelson*Assistant Examiner* — Kathleen M Sims(74) *Attorney, Agent, or Firm* — Brian R. Morrison; Westman, Champlin & Kelly, P.A.(57) **CLAIM**

The ornamental design for a support cleaning system, as shown and described.

DESCRIPTION

Reference is hereby made to co-filed U.S. patent application Ser. No. 12/984,937, dated Jan. 5, 2011, and entitled "Support Cleaning System".

FIG. 1 is a top front perspective view of a support cleaning system;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is an enlarged view of a detail of FIG. 1.

The broken line showing of details in the Figures are included for the purpose of showing environmental portions of the support cleaning system and forms no part of the claimed design.
